UNITED STATES PATENT OFFICE.

JOSEPH McENTEE, OF TIPTON, INDIANA.

PLOW.

No. 927,269.

Specification of Letters Patent.

Patented July 6, 1908.

Application filed January 24, 1908. Serial No. 412,443.

To all whom it may concern:

Be it known that I, JOSEPH McENTEE, a citizen of the United States, residing at Tipton, in the county of Tipton and State of Indiana, have invented new and useful Improvements in Plows, of which the following is a specification.

My invention has relation to plows, and it consists in the construction and arrangement of parts as will be hereinafter described and particularly pointed out in the claim.

In the accompanying drawings:—Figure 1 is a perspective view of a plow embodying the present invention looking toward the mold board side thereof. Fig. 2 is an underneath perspective view of the plow. Fig. 3 is another underneath perspective view of the plow taken at a different angle from Fig. 2. Fig. 4 is a plan view of the mold board, detached. Fig. 5 is a detail perspective view of the share and clamp combined. Fig. 6 is a detail perspective view of the clamp. Fig. 7 is a detail perspective view of the land side or bar. Fig. 8 is a similar view of the plow point.

In carrying out the present invention the mold board 1 which is of the ordinary shape is constructed out of sheet metal being of uniform gage or thickness throughout and for the purpose of this invention the forward edge 30 of the mold board is cut away, as shown at 2 to provide an acute angled notch 3 adapted to receive the correspondingly shaped upper extremity 4 of the plow point 5, the rear edge 35 6 of which fits against the cut away edge 2 of the front of the mold board as shown in Figs. 4 and 5, whereby an interlocked engagement is obtained between the plow point and the mold board.

The share 7 which is illustrated in detail in Fig. 5 is in the form of a straight bar adapted to be rolled out in a mill and given the cross sectional shape shown. In other words, the share comprises a cutting edge 8 which is 45 preferably rounded off toward the front end as shown at 9, the opposite edge being rabbeted throughout its entire length as shown at 10, the depth of said rabbet being just sufficient to receive the bottom edge of the mold board, 50 as shown in Figs. 1 and 2 whereby the upper active surface of the share and mold board are brought flush relatively to each other so as to form a practical continuous surface. The share 7 is further provided with a plurality of sockets or holes 11 which are adapted 55 to receive studs or correspondingly shaped

projections 12 on a clamp 13 which, as shown in Fig. 6, is concavo-convex in cross section, the concavo side thereof being presented toward the under side of the share and mold board. The clamp 13 is provided with holes 14 and the mold board 1 is provided with corresponding holes 15 to receive removable bolts 16 whereby the clamp is held in place and adapted to be removed. One edge of 60 the clamp bears against the share while the other edge thereof bears against the mold board. The share 7 is milled in long bars which are subsequently cut the proper length and hardened thus making a cheap and effective share. The land side or bar 17 may be of any suitable length and has its forward portion cut away at the top as shown at 18 to correspond to the shape of the under side of the mold board and is also provided with 65 an inwardly projecting flange 19 which extends under the mold board and is secured thereto by bolts or other suitable fasteners 20 passing through the mold board and said flange. A portion of the flange 19 is slightly 70 raised as shown at 21 and is provided with a hole 22 which registers with a hole 23 in the plow point the same being adapted to receive a suitable fastener 24, preferably a bolt, whereby the plow point is detachably connected to the flange of the land side or bar 17. 75

In the preferred embodiment of the invention, the fastener 24 consists of a long bolt, one end of which is bent to extend through the holes 22 and 23, the remainder of said 80 bolt extending straight back and passing through a notch in a cross bar 25 the opposite ends of which are secured to the mold board and land side or bar as clearly shown in Fig. 3, a nut 26 being placed on the end of 95 the bolt 24 and screwed up tightly against the brace 25, as shown.

The land side or bar 17 is provided with an adjustable heel piece 27 which is rabbeted as shown at 28 to receive the heel end of the 100 land bar 17 as best illustrated in Fig. 2. Bolts 29 pass horizontally through the land bar 17 and heel piece 27, the latter being provided with vertical slots 31 to allow the rear end of the heel plate to be moved up and 105 down thus disposing the plate bottom portion of the heel piece at an angle to the bottom edge of the land side, which has the effect of uplifting the rear portion of the plow and giving the same a greater downward 110 pitch so as to cause the plow to penetrate deeply into the ground. The forward edge

of the bottom portion of the heel piece is set into a notch in the bottom edge of the land bar as shown at 30.

By means of the construction above described, the share is connected to the mold board without in any way impairing the strength of the mold board thus adapting the mold to be formed out of a suitable blank of sheet metal of the proper gage or thickness. The share being a separate part, may be renewed cheaply and easily and the temper of the plow as a whole will not be interfered with. It will also be seen that the plow point may be readily taken off and renewed and that the depth or penetration of the plow may be accurately adjusted.

I claim:—

A plow comprising a mold board with a plow point having an opening therein, a land side having an inwardly projecting flange secured to the underside of the mold board, a lateral portion 21 of the flange being raised and provided with an opening therein which registers with the opening in the plow point, a plow share having a beveled cutting edge and a continuous longitudinally rabbeted upper portion to receive the lower edge of

the mold board, a concavo-convex clamp having its concave portion contacting with the inner faces of the plow share and mold board and secured thereto, an angular brace having a horizontal portion and an upwardly extended vertical portion provided with a notch, the horizontal portion of the brace being secured to the mold board, a bolt having a bent forward end which is inserted through the registering openings of the plow point and land side, the bolt being rearwardly extended and having its rear end connected to said notch, and means on said connected rear end contacting with said vertical portion of the brace so as to permit of fastening the bent end of the rod in the registering openings of the plow point and mold board, and said landside having an adjustable rabbeted heel piece, substantially as specified.

In testimony whereof I affix my signature in presence of two witnesses.

JOSEPH McENTEE.
